Primary Examiner — Rhea Shields(74) *Attorney, Agent, or Firm* — Ward and Smith, P.A.;
Ryan K. Simmons(57) **CLAIM**

The ornamental design for a closeable container, as shown and described.

DESCRIPTION

FIG. 1 is perspective view of a closeable container showing our new design;

FIG. 2 is a front elevation view thereof, the rear being a mirror image;

FIG. 3 is a right side elevation view thereof, the left side being a mirror image;

FIG. 4 is a top plan view thereof;

FIG. 5 is a bottom plan view thereof;

FIG. 6 is a plan view of the closeable container showing the closeable container in a blank configuration; and,

FIG. 7 is another perspective view of the closeable container showing the closeable container in an open configuration. In the Figures, the dash-dash broken lines are for the purpose of illustrating perforations and form part of the claimed design.
